CLAIM

The ornamental design for a dining chair with arms, as shown.

DESCRIPTION

FIG. 1 is a perspective view of my design for a dining chair with arms;

FIG. 2 is a front elevational view of the chair;

FIG. 3 is a rear elevational view of the chair;

FIG. 4 is a view of one side of the chair;

FIG. 5 shows the opposite side of the chair;

FIG. 6 is a top plan view of the chair;

FIG. 7 is a bottom plan view of the chair; and,

FIG. 8 is a perspective view of my design for a dining chair with side arms which is the same as the chair shown in FIG. 1 and has the same design motif, except that it has a shorter back.

FIG. 8**FIG. 1****FIG. 3****FIG. 2****FIG. 5****FIG. 4****FIG. 6****FIG. 7**
